U.S. CL. D26—1 R

FIG. 1 is an isometric view of a selectable fixed impedance device showing our new design;

FIG. 2 is a top plan view thereof to a reduced scale;

FIG. 3 is a side elevational view thereof to a reduced scale, it being understood that the opposite side is a mirror image of the side shown herein;

FIG. 4 is a bottom plan view thereof to a reduced scale;

FIG. 5 is an end elevational view thereof to a reduced scale; and

FIG. 6 is an end elevational view thereof to a reduced scale, and opposite to that shown in FIG. 5.

We claim:

The ornamental design for a selectable fixed impedance device, as shown and described.
